UNITED STATES PATENT OFFICE.

PHILO B. SHELDON, OF ERIE, PENNSYLVANIA, ASSIGNOR TO THE PHILO BURT MANUFACTURING COMPANY, OF JAMESTOWN, NEW YORK.

DESIGN FOR AN ABDOMINAL CORSET.

SPECIFICATION forming part of Design No. 35,276, dated November 5, 1901.

Application filed August 28, 1901. Serial No. 73,627. Term of patent 14 years.

To all whom it may concern:

Be it known that I, PHILO B. SHELDON, a citizen of the United States, and a resident of Erie, in the county of Erie and State of Pennsylvania, have invented and produced a new and original Design for an Abdominal Corset, of which the following is a specification, reference being had to the accompanying drawings, forming part thereof.

Figure 1 is a front view of an appliance embodying my design, and Fig. 2 is a rear view thereof.

The design presents the appearance of a corset *a*, at the back of which appear two separated and parallel vertically-extended strips *b*, projecting above and below the corset, with lacings passing between them. From the upper portions of these strips above the corset shoulder-straps *c* project and extend

outward and downward back of the corset to 20 near the middle of the strips. At the front below the corset *a* appears a stomach-pad *d*, and from the pad project straps *e*, situate below the corset, extending to the lower ends of the strips *b*.

Having described my invention, what I claim as new, and desire to secure by Letters Patent, is—

The design for an abdominal corset substantially as herein shown and described. 30

In testimony whereof I have signed my name to this specification in the presence of two subscribing witnesses.

PHILO B. SHELDON.
